[57] CLAIM

We claim the ornamental design for a portable tree step, as shown and described.

DESCRIPTION

FIG. 1 is a perspective view of a portable tree step of the claimed design;

FIG. 2 is a top view of the portable tree step of FIG. 1; FIG. 3 is a right side view of the portable tree step of FIG. 1;

FIG. 4 is a front view of the portable tree step of FIG. 1; FIG. 5 is a rear view of the portable tree step of FIG. 1; and, FIG. 6 is a bottom view of the portable tree step of FIG. 1. The broken lines in the drawings are for illustrative purposes only and form no part of the claimed design.
